The ornamental design for a tub for bathing, as shown and described.

DESCRIPTION

In a preferred embodiment, the nature of this product is as a plumbing fixture in the form of a bathing tub primary useful for washing the human body.

FIG. 1 is a left, top, front perspective view of a tub for bathing embodying our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a bottom plan view thereof.

The broken line representations of a drain in FIGS. 2-7, a hole in FIGS. 1-3, 6 and 7, and a cove suitable for mounting a control in FIGS. 1-4, 6 and 7 are for the purpose of illustration only, and form no part of the claimed design.
